UNITED STATES PATENT OFFICE

JOSEPH UNKELBACH, OF JAMAICA, AND HARRY DE BARR, OF BROOKLYN, NEW YORK

DOOR FASTENER

Application filed December 13, 1927. Serial No. 239,660.

Our present invention relates generally to closures, and more particularly to locking devices therefor whereby the amount of opening of the closure is predeterminedly limited.

5 Although we have illustrated and shall hereinafter describe a device constructed in accordance with our invention and applicable primarily to doors of the usual vertically supported type, nevertheless it will be understood 10 that as to certain phases of our invention, an application of this character is not essential and is merely illustrative of the features of our invention.

Where our invention is applied to doors of 15 this character, it is an object to provide a device which will predeterminedly limit the amount by which the door may be opened. Our invention provides means whereby the door may be opened to this limited extent 20 without being further openable from the outside, and in this way the invention will find applicability in connection with stateroom doors, hotel doors, or the like, wherein a secure locking of the door is desired while 25 a partial opening thereof for ventilation purposes is rendered possible.

Our invention provides further means for permitting a similar limited opening of the door in a manner which is openable from the 30 outside, and in connection with this feature of our invention, means are provided for securely holding the door in the predetermined partially opened position. This feature of 35 our invention renders it also applicable in connection with stateroom doors or the like, particularly where such doors are provided with locking means which automatically function when the door is shut.

An important object of our invention is to 40 provide a device of this character which is not only simple in operation and devoid of any complicated necessary manual adjustments, but which is simple to manufacture and to install. An important feature of our 45 invention lies in providing such a device of only three component parts, two of which are designed to be firmly attached to the movable door and a jamb therefor, and the other of which cooperates in an extremely 50 simple manner between the two fixed com-

ponent parts. Furthermore, it is a feature of our invention to provide these component parts of a simple character which permits them to be cast or wrought and which renders them totally devoid of relatively minute adjustable parts such as set screws, springs, or the like.

In accordance with our invention, the three component parts may be designated briefly as a locking bar, and an attaching portion for 55 pivotal association with one end of the locking bar and for firm attachment to one of the closure elements such as the jamb, and an engagement member for firm attachment to the other of the closure elements and for engagement in a slidable manner with the free 60 end of the locking bar. We have found it most satisfactory to provide the free end of the locking bar with an angularly disposed 65 head, and to provide the engagement member with a slotted portion within which the head 70 may slidably engage.

In accordance with one feature of our invention, the head of the locking bar is irre- 75 movably engaged with the slot except when the closure is entirely shut, and in this way a disassociation of the component parts of our device and a consequent opening of the door beyond the predetermined limit is rendered impossible from the outside of the door.

In accordance with another object of our invention, the engagement member is provided with means such as an L-shaped slot with which the free end or angularly disposed 80 head of the locking bar may be selectively as- 85 sociated when it is desired to retain the door in a predetermined partially opened position while at the same time rendering it possible to open the door from the outside.

It is an important feature of our inven- 85 tion, as a result of which the entire device is rendered simple of construction and opera- 90 tion, to provide an arrangement wherein the locking bar swings about its pivoted end in a plane defined by the free edge of the door and the corresponding edge of the jamb. In other words, where our device is employed with a door of the usual character, the lock- 95 ing bar is designed to swing in a substantial- 100 ly vertical plane.

It is another object of our invention to provide our device with means for preventing not only further opening but also reclosing of the door or closure after a predetermined or desired partial opening has been effected. In this way, the device serves not only to limit the amount by which the door may be opened, but it also serves to hold the door in the predetermined partially opened position, and thereby is particularly applicable to stateroom doors or the like where the occupant may desire to retain the door in a fixed partially opened position, yet securely locked from the inside, during the night. The foregoing objects and advantages, as well as others which will hereinafter appear or be pointed out, are accomplished by means of a construction and arrangement of parts illustrated in two embodiments of the invention on the accompanying sheet of drawings wherein—

Figure 1 is a front elevation of our device applied to a door of usual construction, the door being shut and being viewed from the inside;

Figure 2 is a cross-sectional elevation taken substantially along the line 2—2 of Figure 1 and showing the door partially opened in full lines and closed in dotted lines;

Figure 3 is a fragmentary cross-section, in plan, taken substantially along the line 3—3 of Figure 2;

Figure 4 is a view similar to Figure 1 showing a slightly modified construction; and

Figure 5 is a cross-sectional plan view taken substantially along the line 5—5 of Figure 4.

Referring to Figures 1, 2, and 3, 10 represents a door jamb of the usual character, 11 represents a door in closed relationship with the jamb, and 12 represents the edge of the jamb with respect to which the free edge 13 of the door 11 moves into and out of registry when the door is closed or opened. In Figure 1, the door is shown closed, and for this reason, the free edge 13 is in registry with the edge 12 of the jamb 10.

A locking bar 14 is provided at its pivoted end with a substantially spherical portion 15 which engages within a socket or bearing therefor securely fastened to the jamb 10 adjacent to the edge 12. This attaching part is most clearly disclosed in Figure 3 wherein it will be noted that a suitable number of screws 16 pass through a portion 17 which overlies the jamb surface, while a socket portion 18 extends outwardly and provides a chamber thereunder for the accommodation of the spherical end 15. The attaching part is so constructed as to provide a substantially vertical slot 19 in communication with the chamber accommodating the end 15, whereby the bar 14 may freely swing in a substantially vertical plane. It is to be noted that the width of the slot 19 is slightly

greater than the width of the bar portion extending therethrough, so that the movement of the bar is not limited to a strictly vertical swing. In other words, a suitable clearance is provided to render the pivotal association a somewhat universal one. The purpose of this will be obvious hereinafter.

The free end of the bar 14 is bent at substantially right angles to the main portion of the bar and terminates in the head 20. The bar is also advantageously curved midway thereof as shown clearly in Figure 1 so that the head 20 will overlie the marginal portion of the door 11 despite the fact that the pivoting of the bar may have been necessitated a slight distance away from the edges 12 and 13.

The engagement member which cooperates with the head 20 is an elongated member of substantially right-angular cross-section. One portion 21 thereof is designed to be attached to the marginal portion of the door 11 as shown in Figure 1 as by means of screws 22 or the like. The other portion 23 is arranged with its outer surface flush with the free edge 13 of the door 11 and is provided with a longitudinal slot 24 having a width only slightly greater than the width of the bar portion passing therethrough. At its upper end, as viewed in Figures 1 and 2, the slot 24 has an enlargement 25 which permits the withdrawal of the head 20 from engagement with the slot when the door is completely closed, but not otherwise.

The lower end of the slot 24 is positioned at a point on a line extending from the pivot point of the bar substantially perpendicularly to the edges 12 and 13. The purpose of this will be more fully understood hereinafter.

The portion 23 is also provided with an L-shaped slot clearly shown in Figure 2 whereof one arm 26 is aligned with the slot 24 and the other arm 27 extends to the edge of the portion 23.

When the device is installed, the slotted member is so attached to the door that the lower end of the slot 24 is positioned with respect to the pivot point as described in the previous paragraph. The device is then ready for use in either of two ways. Where it is desired to prevent an opening of the door from the outside, the door is first closed, and the head 20 is passed through the enlargement 25 so that it assumes a position substantially like that shown in Figure 1 and the left-hand portion of Figure 2. If the door be now opened, the bar 14 will swing in a substantially vertical plane defined by the edges 12 and 13, and the head 20 will slide downwardly in the slot 24. This sliding is limited in extent by the lower end of the slot 24 so that when the bar 14 is in the full line position of Figure 2, i. e., extending substantially perpendicularly from the pivot point, no further sliding is rendered possible. This position of the bar is one which may be

5 termed a dead center position and the door is prevented from either opening further or being reclosed. If it is desired to close the door, it is necessary to lift the free end of the bar by a slight amount so as to withdraw the bar from this dead center position. Although this slight lifting would seem to be sufficient 10 in order to permit reclosing of the door, nevertheless the clearance in the slot 24 and the general arrangement of the component parts makes it possible to leave the bar in any of a number of positions wherein the door is opened by a degree slightly less than that illustrated in Figure 2. It is not until the bar 15 has been lifted to a point where it forms an angle of approximately 45° to the horizontal that sliding will automatically occur as the door is pushed closed.

It will be obvious that when the bar is associated with the slot 24, the door will be retained in a predetermined partially opened position without any possibility of opening the door further from the outside. It will also be obvious that no adjustments of any 25 character have been necessitated, the simplicity of operation being no less than the simplicity of construction.

The fact that the door is hinged along an axis opposite the free edge 13 results in a 30 movement of this free edge along an arc but this arc has such a large radius with respect to the amount of opening which the device accompanies, that the clearance in the slot 19 as well as in the slot 24 is sufficient to permit 35 the device to function.

When it is desired to employ the device in the other possible manner, i. e., to permit an opening of the door from the outside, the door is first closed, the head removed from the enlargement 25, the door is then opened to the position of Figure 2, and the head 20 is then inserted into the L-shaped slot 27—26. This engagement holds the door in a predetermined partially opened position and prevents 45 automatic locking thereof in a case where the door is provided with such a snap lock.

In Figures 4 and 5 we have illustrated a modification wherein the pivotal attachment is made to a portion of the jamb at right angles to the surface shown in Figure 1. An attaching portion 17' is provided with a raised portion 18' providing a socket for the accommodation of the enlarged head 15' of the bar 14'. In this construction, the bar may 55 be entirely straight as shown in Figure 4. The operation of the device is exactly like that hereinbefore described, and it will be noted that the rod swings in a plane substantially perpendicular to the angularly disposed free end of the bar, as before. In this construction, a sufficient clearance is provided at 19' to permit the device to function as the door swings about its hinge axis.

It will of course be understood that our invention is not limited to the specific embodiment illustrated. For example, the relatively fixed component parts of the device may be interchanged so that the slotted member is on the jamb and the pivoted member on the door. Similarly, the device may be applied with equal facility to such closures as transoms or the like. Nor is it essential 70 that the slotted member be associated with the edge of a movable closure member opposite a hinge axis. Thus, the device could be used with equal facility in connection with the top edge of the door illustrated in the drawings. This would be impractical where the device is employed with a door, but in the case of a transom, it may be more convenient 75 to arrange the device in association with one of the edges adjacent to the hinged edge. In its essence, the device is applicable to closures wherein there is a jamb element and a movable element, and wherein the movable element 80 has a free edge moving into and out of registry with an edge of the jamb element.

In general, it will be obvious that the details herein described and illustrated for the purpose of explaining the nature of our invention may be made by those skilled in the art without departing from the spirit and scope of the invention as expressed in the appended claim. It is therefore intended that these details be interpreted as illustrative and 95 not in a limiting sense.

Having thus described our invention and illustrated its use, what we claim as new and desire to secure by Letters Patent is—

In combination with a jamb and a door the free edge of which moves into and out of registry with the jamb, a device for retaining the door open a predetermined limited amount comprising in combination, a normally vertically disposed fastening bar pivoted at its lower end to the jamb, the free end of said bar being bent at substantially right angles to the main portion of the bar and terminating in an enlarged head, means carried by the door adjacent the free edge thereof for cooperating with said enlarged head, said means comprising an elongated member of substantially right angular cross-section, one portion of said elongated member being arranged with its outer surface flush with the free edge of the door and provided with a longitudinal slot, the upper end of said slot being enlarged to permit the withdrawal of the enlarged head of the bar from said slot only when the door is in closed position, and the lower end of said slot being positioned upon a line extending from the pivot point of the bar substantially at a right angle to the free edge of the door.

In witness whereof we have signed this 125 specification.

HARRY DE BARR.
JOSEPH UNKELBACH.
